UNITED STATES PATENT OFFICE

DOUGLAS H. DYER AND WILLIAM F. RODENKIRCHEN, OF ST. PAUL, MINNESOTA; SAID
DOUGLAS H. DYER ASSIGNOR TO WILLIAM M. DYER, OF ST. PAUL, MINNESOTA

TRAFFIC SIGNAL

Application filed November 14, 1931. Serial No. 575,083.

My invention relates to traffic signal devices of the class in which electrically controlled and illuminable means display alternating stop and go signals at street or road intersections. It is of the suspended, overhead type though applicable as a corner signal mounted on posts, the preferred use of our device being overhead and centrally over the middle of an intersection at a height of approximately 15 feet to 20 feet or more over the road surface and therefore clearly visible to motorists and pedestrians at various ranges.

The invention includes a number of new and novel features as hereinafter fully set forth, reference being had to the accompanying drawings, in which,

Fig. 1 is a side elevation of the signal device.

Fig. 2 is a diagrammatic plan view of a street intersection and one of our devices suspended in the middle of the intersection.

Fig. 3 is an enlarged sectional view on a horizontal plane, of approximately one half of the signal chamber, as on line 3—3 in Fig. 1 and showing certain auxiliary vanes adapted for use where street approaches to intersections are angular instead of at right angles.

Fig. 4 is a sectional view corresponding to Fig. 3, as on line 4—4 of Fig. 1.

Fig. 5 is an approximately central cross sectional view of the signal device.

Fig. 6 is a horizontal plan view in enlarged scale, as on line 6—6 in Fig. 5 revealing the train of gears and co-acting disc means causing intermittent rotation of the signal-cylinder.

Fig. 7 is a detail sectional view radially of one of the gears and its disc as on line 7—7 of Fig. 6.

Referring to the drawings by reference numerals, in Fig. 2 10 designates a street intersection where a north and south street 10N intersects an east and west street 10E. 11 are diagonal wires or cables suitably connected at the center of the intersection to the stationary cover or hood member 12 of our device and extending at suitable height to posts 13 or buildings 14, as the case may

be, at the respective corners. 15 are insulators in said cables in necessary positions. One corner post, 13A, may be provided with a suitable windlass device having a crank 16 for a cable 17 guided and extended to 55 and over the center of hood 12, thence extended downwardly to engage the upper extremity of our signal device which is capable of being let down from its normal signaling position directly under said hood to 60 toward the street, by means of said windlass and cable, said raising and lowering means being well known for arc-lighting devices. 18 is a flexible electric conduit of a length such as to conduct electric current to a pair 65 of stationary contact-sockets 19 in the head 12H of the hood 12. Said hood comprises other than its head 12H a downwardly flared preferably circular shield and the sockets 19 thereof are open downwardly to slidably 70 receive a pair of contact fingers 20 of the signal device to provide circuit closing means as cable 20A to the motor and illuminable signal means of our signal head, the latter presently to be fully described. It 75 will be readily understood that any suitable raising and lowering means for our signal head may be employed, it being further understood that the lowering of the signal device is preferred to be limited so that its 80 lowered position is about three or four feet above the street level and obviously then in an accessible position for repairs or adjustments.

Our signal housing or head comprises 85 preferably an upright cylindrical member with a conical top 21 to fit snugly and concentrically the corresponding under side of the stationary hood 12. The said cylindrical body comprises an upper cylindrical 90 motor- and mechanism-chamber designated A and below this an integral cylindrical signal chamber designated B. The former chamber (A) has a floor 22 on which is mounted an electric motor 23 with gear reduction housing 23H having a downwardly directed drive shaft 24 extending below floor 22 where said shaft carries a drive pinion 95 25 (see Figs. 5 and 6). During operation of the motor this drive pinion provides con- 100

tinuous motion to certain gear means just below floor 22 and just over the upper part of signal housing B. Said gear means and their operative relation to certain signal means in housing B will now be described.

The drive-pinion 25 meshes with one of 4 like gears 26, 26A, 26B and 26C mounted to rotate on stub shafts 27 fixed in plate 22, 90 degrees apart on a circle concentric of 10 the housing and all said 4 gears meshing with a central gear 28 likewise rotatable on a stub shaft 27A and the said gear 28 being of same size as the 4 gears. Thus all the 4 circularly arranged gears are rotated simultaneously and in same direction of rotation, gear 26 being the primary driven gear and imparting said rotary motion through the center 28 gear to the gears 26A, B and C.

To each of the 4 gears is fixed concentrically a circular plate or disc 29, projecting radially outward and each provided near its outer rim with a circular row of apertures 30. The gears 26, 26A, 26B and 26C are of various width or tooth-face preferably all 25 flush at their tops and the plates 29 are fixed to their under sides and therefore in different planes. Each plate 29 is provided with a contact pin 31 adapted to be removably fixed in any one of its apertures.

30 The lower two of the plates have their pins projecting upwardly while the upper plates have their pins 31 projecting downwardly (see Figs. 5 and 6). During rotation of the gears these pins 31 make arcuate 35 movement through the overlapping adjacent parts of the discs and all four of said pins contact consecutively with and move a radial arm 32A of the vertical, central shaft 32 of a signal cylinder in chamber B, 40 thus imparting regulated and intermittent movement of said signal cylinder. Said arm 32A is in the path of movement of all of the disc pins 31 and contacted with by only one at a time. For example, in Fig. 6, pin 45 31 of plate 29 on gear 26A is just contacting with arm 32A while the latter is moving in direction indicated by arrow 33. The said pin will of course rock the arm toward the right and continued movement of the pin releases it from contact with the arm, the latter stopping at point 34 where it is subsequently engaged by pin 31 of plate 29 of gear 26B, moving in direction of arrow 35 thereby giving arm 32A another arcuate 50 movement toward gear 26C. Thus shaft 32 is rotated intermittently by the successive contacts of pins 31, and certain illuminated signal means are exposed consecutively to the traffic lanes. The arm 32A is moved 90 55 degrees of a circle each movement but the timing of such movements is of course variable according to the positions of pins 31 on the respective plates 29. This adjustability of timing is of course important where traffic conditions vary at street intersections.

The signal chamber B is as previously stated preferably an upright, cylindrical device integral of chamber A and below it, being shown as slightly smaller in diameter than chamber A. Said chamber B has a 70 fixed base 36 with a central bearing 36B to suitably and rotatably support the lower end of shaft 32 (see Fig. 5). 37 is a horizontal spider fixed on upper part of shaft 32, as at 75 38, said spider circular exteriorly and adapted to retain in said outer part the upper end of an upright translucent cylinder designated C as a whole, the lower end of said cylinder being free, or supported on any suitable friction reducing means at 39. This cylinder 80 comprises a circular row of colored arcuate panels illuminated by a number of electric bulbs 40 (preferably 4 in number) receiving current from any electric source.

The chamber B has four exterior openings separated by upright bars 41, 90 degrees apart, and connecting the base 36 rigidly with the lower part of chamber A, within said bars 41 is retained concentric of cylinder C and exteriorly of the latter another cylinder 42 of transparent material, this latter cylinder being stationary.

The signal cylinder is preferably made with two opposite green panels designated C2 in Figs. 1 and 4, and at right angles 95 thereto another pair of opposite panels of red color and designated C3, said red panels illuminated of course to simultaneously indicate "stop" to traffic while the green panels indicate "go" or traffic flow.

C4 are a pair of smaller panels comprising a part of the signal cylinder and are diametrically opposite and interposed between adjacent parts of red and green panels. The said smaller panels are of any 100 suitable color preferably orange or yellow. When a change of signal from "go" to "stop" is to take place, the signal cylinder receives a quarter turn as to the right in upper part of Fig. 4 and a panel C4 follows panel C2 across the opening, (indicated as N) of the chamber B, flashing the yellow signal across the opening until the following red panel C3 is exposed fully in said opening, the entire cylinder coming to a stop 110 when the red panel is exposed at N where previously the green panel had been exposed, the yellow panel stopping simultaneously behind one of the bars 41 and is unseen until the following traffic change is to 115 take place. The signal cylinder remains stationary for any set interval governed by the location of pins 31 on the respective plates 29. It is evident that when one pin 31 of a plate 29 has left contact with arm 32A 120 motion of cylinder C ceases until the next pin 31 of the succeedingly acting rotary plate 29 contacts with and moves the signal-cylinder arm 32A.

In Fig. 4 one of the bars 41 of the signal 125

chamber is shown hollowed interiorly to provide a channel for necessary electric wires 43 to the bulbs 40, and further channels for this purpose may be provided as at 5 44 on the under side of base 36 (see Fig. 1) for the wiring to sockets 40S of said bulbs.

In Figs. 1 and 3 is shown certain means consisting of sheet metal vanes 45V of V-shape in cross section, each vane attached at 10 its apex to a vertical rod 45 retained pivotally and exteriorly of a vertical frame bar 41 in upper and lower lugs 46. The ends of said rods have protruding threaded ends for nuts 47, adjustment of which holds 15 the rods 45 and their vanes in any desired position. These vanes, of course, are useful for intersections where streets approach at various angles and shut off visibility of red signal by traffic approaching angularly, or 20 vice-versa. The angle between the two sides of the vanes must of course be determined according to conditions at the intersection where the signal is installed.

In Figs. 1 and 5, 48 are suitable openings 25 in the upper part of the wall of chamber A providing outlet for air circulated by a small fan 49 rotated by the motor 23. Thus any excessive heat generated by the motor or the lights within the device is disposed of 30 and eliminating the possibility of frost forming on the signal means.

It will now be understood that our signal device is an inexpensive installation. There are no automatic electric contacts. 35 Power line runs only to the fixed upper housing. Any suitable means (not shown) may be used to insure proper electric contact of the fingers 20 with the fixed contact sockets provided therefor.

40 The signal cylinder C may be grooved perimetricaly at its lower edge to ride on four half-ball bearings 50 suitably seated in the ring 39 of base 36.

A number of modifications of details pertaining to ease of operation, proportions of gears and other operating details may be embodied without departing from the scope and spirit of our invention.

An important feature is that the green 50 lights are followed by red (no orange) light, green lights being of such length that red does not come in until the two orange lights are fully exposed. This, it will be noted, gives an advance warning to the flowing 55 traffic.

We claim:

1. In a traffic signal of the class described comprising an upright cylindrical housing adapted to be mounted at a traffic intersection; said cylindrical housing embodying an upper mechanism chamber and therebelow a signal chamber, and said signal chamber provided with a plurality of horizontally exposed circularly arranged openings, a stationary outer cylindrical glass closing said

openings, an inner translucent signal cylinder, a vertical central shaft rotatable in said signal chamber, a web member fixed on said shaft and retaining the signal cylinder in concentric relation thereto, an actuator arm 70 in the upper chamber on said shaft, continuously operating driving means suitably mounted in the upper chamber, means in said chamber and actuated by said driving means to cause contact with said actuator arm at predetermined intervals to rotate the said signal cylinder one-quarter of a circle for each contact of the arm.

2. The structure specified in claim 1, in which said signal cylinder comprises a plurality of arcuate, colored, panel sections arranged to be exposed two panels of like color in opposite windows and two panels of another color, as green, in the other two windows, simultaneously. 80

3. The structure specified in claim 1, in which said signal cylinder comprises a plurality of arcuate, colored, panel sections arranged to be exposed two panels of like color, as red, in opposite windows and two panels of another color, as green, in the other two windows, simultaneously, and two narrow translucent panels in said signal cylinder of a color distinctive from the color of the first described panels, said narrow panels located one adjacent the edge of each green panel, to follow in the path of movement of its green panel, for the purpose set forth. 90

4. In a traffic signal of the class described, 100 an upright cylindrical housing with an upper mechanism chamber and a lower signal chamber with four horizontally exposed windows facing diametrically oppositely in pairs, an upright rotatable signal cylinder in the signal housing and comprising a series of arcuate suitably colored sections; continuously operatable driving means for rotating said signal cylinder to expose consecutively, distinctive colored panels in said windows, said driving means comprising a motor with a primary drive pinion meshing with one of a train of four circularly arranged gears, a central gear rotatably mounted concentrically between said four gears and meshing with all of them, a circular plate fixed concentric on each of said four gears, each plate provided with a circular row of apertures and a contact pin removably insertible in any of said apertures, a vertical shaft central of the signal cylinder and fixedly connected thereto, an actuator arm fixed on said shaft and arranged in the circular path of movement of all said contact pins, the contacting action of each said pin with the said arm calculated to provide a quarter of a circular turn of the vertical shaft and the signal cylinder. 115

5. The structure specified in claim 4, in which said signal chamber comprises fur- 120

125

130

ther four upright exterior frame arms arranged in quadrangular formation concentric of the cylinder and define the sides of the windows thereof.

5 6. The structure specified in claim 4, in which said signal chamber comprises further four upright exterior frame bars comprising the sides of the respective windows, and adjustable vane members one for each said upright arm or bar, each vane comprising an
